DESIGN FOR A SCARF

Patricia Quinn O'Hara, New York, N. Y.

Application May 26, 1937, Serial No. 69,555

Term of patent 7 years

To all whom it may concern:

Be it known that Patricia Quinn O'Hara, a citizen of the United States and resident of New York, in the county of New York and State of New York, has invented a new, original, and ornamental Design for a Scarf, of which the following is a specification, reference being had to the accompanying drawing, forming part thereof, and in which;

Fig. 1 is a plan view of the scarf, showing my design, wherein the outwardly broadening arm and neck members, extending from the tailored back portion, are folded upon themselves, in accordance with my design.

Fig. 2 illustrates the scarf showing the arm and neck members in developed, unfolded position.

I claim:

The ornamental design for a scarf, as shown and described.

PATRICIA QUINN O'HARA.
